UNITED STATES PATENT OFFICE

MAX TROY, OF BROOKLYN, NEW YORK, ASSIGNOR TO CHARLES E. BONOFF, OF BROOKLYN, NEW YORK

WASHING MACHINE

Application filed January 8, 1929. Serial No. 331,051.

The present invention relates to washing machines or the like of the drum type and aims to provide certain improvements therein. More particularly it relates to improvements in the doors and door-locking mechanisms of such machines whereby the possibility of loss or damage to clothes treated in the drum is reduced to a minimum, and the operation of removing the clothes from the drum is greatly facilitated.

According to the present invention I provide the drum with a hinged door, which, in open position, is adapted to bridge the space between the drum and the housing within which it is movable. Where the drum is divided into radial chambers, the door serves as an extension for the radial wall and provides a continuous slide over which the clothes from the drum can be removed or slid directly into a receiving receptacle. Preferably, hinged double doors are used on the drums, and each door section is provided with independent locking means, and both door sections are provided with cooperating means for insuring the locking of both said door sections. The invention also embodies other features of novelty which will be hereinafter more fully described.

A preferred embodiment of my invention is illustrated in the accompanying drawings wherein,

Figure 1 is a front elevation with parts broken away, of a washing drum unit.

Fig. 2 is an enlarged transverse section taken substantially along the plane of the line 2—2 of Fig. 1.

Fig. 3 is a radial section taken substantially along the plane of the line 3—3 of Fig. 1 showing the lower door section in closed, latched and locked position.

Fig. 4 is a partial section similar to Fig. 3 showing the door in closed, unlatched position.

Fig. 5 is a section taken substantially along the plane of the line 5—5 of Fig. 3.

Fig. 6 is a front elevation of the locking mechanism for the upper door section with its cover plate removed.

Fig. 7 is a section taken substantially along the plane of the line 7—7 of Fig. 6.

Fig. 8 is a radial section taken substantially along the plane of the line 8—8 of Fig. 1. Referring to the drawings, let 10 indicate the washing drum unit which is of cylindrical form, and as herein shown, is perforated with openings 10' and divided by the radial walls 11, 11' and 11² into three radial chambers 12, 12' and 12² respectively. Each of these chambers is provided with an opening 13 in its cylindrical wall, and with interior baffles 14 and 15 of conventional design for promoting the washing action. The drum 10 is mounted upon a horizontal axis in concentric spaced relation to an enclosing housing 16 (shown in dot and dash line in Fig. 2), said outer housing having the conventional opening and closure therefor (not shown), the lower edge of said opening designated by the reference numeral 17, being preferably located below the axis of the housing. The outer housing 16 is preferably stationary, while the drum 10 is adapted to be rotated therein. The parts thus far described constitute a form of washing machine now in use.

According to the present invention I provide a novel closure means for the opening 13 in the drum; and also novel locking means for said closure, the advantages of which will be apparent from the detailed description of these improvements which follows.

Instead of the conventional arcuate sliding doors now used on machines of the type described, I employ a hinged double door herein indicated by the reference numerals 18 and 19, which door sections are hinged to the drum at 20 and 21 respectively through the medium of butt hinges 22 and 23 respectively. In order to insure a perfect closure for said door sections and eliminate all possibility of recesses or openings in which the lint or clothes may catch and damage thereto be done, I provide a jamb 24 which extends completely around the opening 13 so that the door sections 18 and 19 will have a flush seating. To further insure the flush continuity of the inner wall of the door sections and also to insure against the outward pressure against said door sections, I extend the wall of the door section 19 outwardly to provide

a flange 26 which serves in closed position of said door section as a jamb for the adjacent edge on the door section 18, the body portion of which carries an overhanging flanged member 27, the base of which is adapted to seat against the jamb 26, while the overhanging and re-bent portion 28 which provides a channel 29 is adapted to engage over a longitudinal rib 30 on the door section 19, for a purpose which will presently appear.

Each of the door sections 18 and 19 are provided with independent locking or latching means for securing said sections in closed position, and said sections are also provided with cooperating means for insuring the proper locking of each of the sections when the door is closed.

The locking means on the door section 18 is in the form of a pair of oppositely-movable lock bolts 31 and 32, the outer ends of which taper inwardly, as shown at 33, and are adapted to engage in recesses 34 and 35 respectively formed in lugs or abutments 36 and 37 respectively affixed to the inner wall of the drum. The inner ends of the bolts 31 and 32 are oppositely screw-threaded, as shown at 38 and 39 respectively, and are moved longitudinally in opposite directions through the medium of a spiral gear 39' into which they are screw-threaded, which, in turn, is adapted to be rotated by a worm 40 having a socket 40' into which a suitable key 40² may be inserted. To insure rectilinear movement for the bolts 31 and 32 they are provided with polygonal portions 42 which are slidable and non-rotatable in lugs 43 carried by the inner wall of the door section. To protect the lock mechanism and at the same time insure against any of the lock parts doing injury to clothes within the drum, the entire lock mechanism is enclosed within a housing 44 which provides an additional internal baffle rib within the chamber. Preferably the lugs 36 and 37 are so shaped as to form continuations of the housing 44 and thus render the baffle rib continuous across the chamber. To protect the lock mechanism at the outside of the drum, a suitable cover plate 45 is provided, which cover plate also carries part of the bearings for the spiral gear 39' and the worm 40.

The latching means on the door section 19 consist of a pair of slotted slide members 46 formed at their inner ends with finger-engaging flanges 47, and at their outer end with pins 48 engageable in sockets formed in lugs 49 affixed to the outer wall of the drum. To guide said slide members 46, a screw or pin 50 is passed through the slot therein and the pin 48 is guided through an opening in an outwardly-extending flange 51 carried by a member 52 affixed to the outer wall of the door section. It will be apparent from an inspection of the slide members 46 that their

movement toward each other is limited by the slots therein. It will also be apparent from an inspection of Figs. 1, 3 and 4 that the overhanging flange 28 on the door section 18 is of a length slightly in excess of the rib 30 on the door section 19, and that said flange is adapted to extend beyond each end of said rib a distance such that it will engage over said rib when the slides 46 are in latching position, but will be hindered in such engagement when the slides 46 are in unlatching position. It will also be noted that in order for the door section 18 to properly seat against the jambs 24 and 26, the flange 28 must engage over the rib 30. Hence it will be appreciated that the flange 28 and rib 30 constitute means for insuring the proper closing of both door sections and the locking of the door section 19.

It will be apparent that the door sections may be hinged to the drum in any conventional manner, but I prefer to employ the improved butt hinges 22 and 23 which extend substantially the full width of the drum section. These butt hinges each consist of a pair of leaves 53, one attached to the drum and the other to a door section, and each leaf in turn composed of a plurality of abutting sections 54. Preferably the terminal sections are removably secured to the respective parts by screws 55, whereas the intermediate sections are riveted or non-removably secured to the respective parts. Also, the hinge pins 20 and 21 are made in sections corresponding to the sections of the leaves. The advantage of this construction, it will be apparent, resides in the fact that should any portion of the hinge become defective or inoperative, it is not necessary to remove the entire hinge but merely to remove the end hinge sections, whereupon access can be gained to any intermediate section.

As hereinbefore stated, the axis of the drum is above the bottom edge 17 of the opening in the outer housing 16. Hence when the openings 13 and 16 are brought into coincidence and the door section 19 opened to rest against the edge 17, it will be apparent that said door section 19 serves as a continuation of the inclined radial wall 11 and hence serves the dual function of bridging the space between the drum and the outer housing and of providing a continuous inclined slide, so that clothes can be easily moved or slid from within the chamber 12 directly into a receptacle 56 positioned beneath the open door section 19. All danger of clothes falling between the drum and outer housing is thus overcome and the entire operation of removing the clothes from the chamber greatly facilitated.

Although in the foregoing description I have not made specific reference to the character of the materials employed nor the precise manner in which the parts are joined or

connected, and have made specific reference to but a single section of a drum, it is to be understood that the device is applicable equally well to a single section, multiple section or Pullman type of machine, and that the details of construction may be varied within the realm of mechanical and engineering skill. Hence, modifications of the device as described may be resorted to without departing from the spirit of the invention.

What I claim is:

1. A washing machine comprising a drum having an opening, a door for said opening, locking means for said door, and baffle ribs on the inner wall of the drum, said locking means comprising a pair of oppositely-movable lock bolts and a pair of recessed keepers for the ends of said bolts, said bolts and said keepers being enclosed within a baffle rib.
2. A washing machine comprising a drum having an opening, a door for said opening, locking means for said door, and baffle ribs on the inner wall of the drum, said locking means comprising a pair of oppositely-movable lock bolts having tapered ends and a pair of recessed keepers for the tapered ends of said bolts, means for simultaneously moving said bolts, said bolts and said keepers being enclosed within a baffle rib.

In witness whereof, I have hereunto signed my name.

MAX TROY.
